PACKAGE

Harry Stewart Jones, London, Ontario, Canada

Application May 14, 1934, Serial No. 725,623

2 Claims. (Cl. 229—87)

My invention relates to improvements in packages which may be used either for the display of goods, or for a container, or for merely wrapping the same.

5 One object of my invention is to provide a combined display card and package which may be opened or closed quickly, as desired, without the necessity of adding sealing or fastening means, and which when so open will afford a neat and substantial support and display for the goods.

10 Another object is to provide a combined display card and package, the fastening means for holding the same closed being in itself an ornamental feature to enhance the attractiveness of 15 the display.

20 A further and important object is to provide a package adapted to be quickly and easily opened and closed by interlocking means constructed in such a manner that the tendency of the package 25 to spring open, due to the natural spring of the board and the pressure of the goods inside, will enhance the security thereof.

Other objects as well as many advantages will 30 become apparent in the following description of my invention supplemented by drawing, in which:

Fig. 1 is an elevation of one package as used for display;

Fig. 2 is a plan view of the blank required to make up the same;

35 Fig. 3 is a top plan view of the same when closed;

Fig. 4 is an end view thereof;

Fig. 5 is a view of a portion of each flap showing the manner in which they are held together.

40 Similar characters of reference refer to corresponding parts in all the views.

The package, as shown, consists of a wrapper of stiff or dense material 10, such as stiff cardboard, provided with flaps 11 adapted to close over

45 the goods, which goods may be preferably held to the central part of the wrapper, as shown in Fig. 1, by stitching, metal fasteners or other means. The flaps may be spaced from the central portion of the wrapper by integral side walls 12 formed by creases 13.

The flaps are joined by means of series of indentations and tongues on each edge thereof, adapted to mesh together, as shown in Figs. 3 and 4. The tongues are denoted by 14, and the

50 grooves by 15. It will be noticed that they are alternately set so that when the package is folded the tongues of one side of the package will register with the grooves on the other side thereof. The tongues are preferably made to enter between two respective tongues of the other flap in such a way

as to lie underneath the flap. The effect of the tongues lying underneath the flap, as shown in Figs. 3 and 4, is to lock the two flaps so that the same will not rise upwardly. It is therefore evident that the more the packages tend to open or spread out the more securely will the tongues adhere to the underside of the respective flaps and also that any pressure caused by the resiliency of the goods enclosed will enhance this feature.

5 The tongues of one side and obviously the 10 grooves in the same side may be longer than those of the other flap so as to more easily mesh the same by inserting the shorter tongues underneath the opposite and longer flap, as a first op-

eration, and then following with the insertion 15 of the opposite tongues under the second flap. It is also obvious that, in a smaller package, the edges of each flap may be provided with only one

or a few indentations and tongues to provide a proper closure therefor. I have, for example, in 20 mind a razor blade package in which the edge of one flap has only one tongue and the other edge of the other flap one corresponding groove,

which provides a very satisfactory closure in this 25 case.

When used as a display as previously stated, the goods, such as a pair of ankle supporters shown as an example in Fig. 1, may be fastened to the central portion of the package and any suitable printing or illustration may appear 30 around the goods and on the inside of the flaps as well as on the outside, such as represented by straight lines in Figs. 1 and 3.

35 Although shown and described on a flat package, my invention may be incorporated in a container or package having a number of sides, the free ends having corresponding flaps provided with tongues and one or more grooves, the tongues underlying the flaps as already mentioned.

40 From the foregoing it is evident that packages so constructed are adapted to numerous uses, are quickly and securely closed and opened as often as required without injuring the wrappers and affording absolute protection to the contents thereof. It is also obvious that goods so put 45 up may be displayed with advantage, returned to stock, and afterwards handed to the purchaser in the original neat and compact form.

What I claim is:

50 1. A wrapper formed of an imperforate non-metallic thin foldable one-piece web-like body, one side edge of said web being formed centrally with an extension, the other side edge of said web extending in a single plane throughout, said web having finished end edges, each end edge con-

sisting of alternately disposed completely open notches and tongues, the tongues and notches of one end edge being alternately disposed with respect to the tongues and notches of the other end edge, the tongues of one end edge extending through the notches of and bearing against the inner face of said web leading from the other end edge and providing a sole means for connecting the ends of the web together for retaining the web in wrapping position.

2. A wrapper formed of an imperforate non-metallic thin foldable one-piece web-like body of oblong contour, said web having one of its side edges formed centrally with an extension and its other side edge extending in a single plane throughout, said web provided with two spaced pairs of transverse scores, the scores of each pair being arranged in parallel spaced relation, the portion of the web between each pair of scores being of the same width, each pair

of scores being located between the transverse median and one end of the web, the part of said web between the scores of each pair of scores forming the side walls of a package when the web is folded, that part of said web between the inner scores of said pairs of scores providing the bottom of a package when the web is folded, the parts of the web between the outer scores of the pair of scores and the ends of the web forming a pair of oppositely foldable front closure flaps for a package when the web is folded, each of said flaps having a finished outer end edge formed with one or more open notches and one or more tongues, the notches and tongues of the outer end edges of said flaps coacting with each other and the tongues of the outer end edges of one flap coacting with the inner face of the other flap for detachably connecting said flaps together to close the front of a package.

HARRY STEWART JONES. 20
